UNITED STATES PATENT OFFICE.

FRANCIS G. BATES, OF PHILADELPHIA, PENNSYLVANIA.

ROTARY PUMP.

SPECIFICATION forming part of Letters Patent No. 730,081, dated June 2, 1903.

Application filed November 18, 1901. Serial No. 82,727. (No model.)

To all whom it may concern:

Be it known that I, FRANCIS G. BATES, a citizen of the United States, residing in Philadelphia, Pennsylvania, have invented certain 5 Improvements in Rotary Pumps, of which the following is a specification.

One object of my invention is to construct a rotary pump of improved form in which a full area of opening or discharge, or both, is 10 provided for each of the pistons when the pump is of the duplex or multiple type, and a still further object being to simplify and cheapen the construction of the pistons. These objects I attain in the manner herein- 15 after set forth, reference being had to the accompanying drawings, in which—

Figure 1 is a transverse section of a rotary pump constructed in accordance with my invention. Fig. 2 is a longitudinal section of 20 the same, partly on the line *a*, Fig. 1, and partly on the line *b*, Fig. 1, the piston and piston-shaft being shown in elevation; and Fig. 3 is a sectional view of the piston-shaft and its two pistons.

25 1 represents the cylinder or casing of the pump, which in the present instance is of the duplex type, being bored out on each side of a central partition 2, so as to receive a rotating piston 3, which is eccentric in respect to the shaft 4, one of the pistons being set at one hundred and eighty degrees in respect to the other and each piston having rigidly secured upon it a sleeve 5, providing a bearing for a series of rollers 6, the latter carrying an 30 outer ring 7, which constitutes the contacting ring of the piston, and as the eccentric portion of the latter rotates is caused to rock or oscillate, so as to bring all portions of its periphery successively in contact with the bore 35 of the chamber in which it works. My invention is, however, applicable to pumps having rotating pistons of other types.

Each ring 7 carries laterally-expanded packings 9, which bear, respectively, against 40 the partition 2 and against the opposite heads 10 of the cylinder, so as to prevent leakage at either end of either piston.

Communication between the piston-chamber on opposite sides of the point of contact of 45 the piston-ring 7 with the cylinder is prevented by a sliding plate 11, which has at its in-

ner end a rounded rib 12, adapted to a rounded seat in the piston-ring 7 and in retainer-blocks 13, carried thereby, this plate sliding in suitable guides 14 and the piston-ring 7 55 rocking on the rounded lower end of the plate as said ring is carried up and down and from side to side in the piston-chamber by the rotation of the eccentric piston.

The top of the cylinder is provided with a 60 cap 15, which has a central partition 16, receiving the upper portions of the guides 14 for the sliding plate 11, said partition, in connection with these guides, serving to form induction and eduction passages for each of the 65 piston-chambers of the pump, each induction and eduction passage being divided by a horizontal partition 17 into two portions. Thus the portion of the induction-passage above the partition is represented at 19 and the portion below the same at 19^a, while the upper portion of the eduction-passage is represented at 20 and the lower portion of the same at 20^a.

The partition 17 has a number of ported 70 seats 21 for induction-valves 22 and eduction- 75 valves 23, the induction-valves being contained in the portion 19^a of the induction-passage and opening toward the piston-chambers and the eduction-valves being contained in the portion 20 of the eduction-passage and 80 opening away from the piston-chambers, each valve being normally kept closed against its seat by means of a coiled spring 24, interposed between the valve and a cap 25, carried by a stud or spindle 26, which projects 85 from the valve-seat. These valves thus serve to prevent backflow of fluid from the eduction-passage into the cylinder or from the latter into the induction-passage when the motion of the pistons is suddenly arrested 90 from any cause.

Each piston-chamber is in communication with all of the induction and eduction valves by reason of the formation of openings 27 in the partition 2, so that each piston can 95 draw through the ports of all of the induction-valve seats and discharge through the ports of all of the eduction-valve seats, easy flow of the liquid to and from the piston-chambers being thereby insured and interference with the operation of the pump due to 100 excessive friction upon the fluid being pre-

vented. The same construction can of course be applied to pumps having more than two piston-chambers.

Each of the eccentric pistons is, as shown in Fig. 3, provided with a flange 30 at its inner end, which flange serves as a stop for the sleeve 5, which is seated firmly upon the piston and is prevented from rotating independently thereof by means of a key 31, as shown in Fig. 1.

Each of the sleeves 5 has at its inner end a flange 32, which serves as a stop for one end of each of the series of rollers 6 and also for one end of the piston-ring 7, the rollers and piston-ring being retained in the opposite direction by means of a ring 33, screwed upon the end of the sleeve 5, as shown in Fig. 3. By this means a ready fitting together of the parts is facilitated, the piston being introduced from one end of the cylinder structure, and in the case of a duplex pump one of the pistons passing through an opening 35, formed in the central partition 2, so that the parts carried by one piston can be introduced through one end of the cylinder and those carried by the other piston can be introduced through the opposite end of the cylinder before applying the heads 10.

The piston-shaft has a central oil-supply passage 36, with radial branches 37, leading to the raceway for the antifriction-rollers 6, and the bearing-hub on each of the heads 10 of the cylinder carries a split bearing 39 for the piston-shaft and has a well 40, into which

dips an oil-supplying ring 41, resting upon 35 the shaft and serving to deliver oil to a lateral passage 42, leading to the central oil way or duct of the shaft, as shown in Fig. 3.

Having thus described my invention, I claim and desire to secure by Letters Patent—

1. A cylinder having two or more piston-chambers, each with rotary piston and sliding separator-plate, and also with induction and eduction passages each divided by a partition having ported valve-seats to which are adapted self-closing induction and eduction valves, the induction and eduction passage of each piston-chamber being in free communication with the corresponding induction or eduction passage of another piston chamber or chambers, substantially as specified. 45

2. The combination of the eccentric piston with the sleeve surrounding the same and secured thereto, said sleeve having a flange at 55 one end, the piston-ring, the series of rollers interposed between the same and the sleeve, and a ring secured to said sleeve and serving to confine the piston-ring and rollers longitudinally between it and the flange of the 60 sleeve, substantially as specified.

In testimony whereof I have signed my name to this specification in the presence of two subscribing witnesses.

FRANCIS G. BATES.
